Patented Sept. 21, 1926.

1,600,515

UNITED STATES PATENT OFFICE.

GENEVIEVE L. SECOY, OF CHARLES CITY, IOWA.

SWEEPING COMPOUND.

No Drawing.

Application filed February 11, 1925. Serial No. 8,535.

The purpose of my invention is to provide a compound for use in sweeping floors.

More particularly, it is my purpose to provide such a compound having ingredients, which can be secured, prepared and compounded at a minimum of expense for materials and labor.

Another object of my invention is to provide such a compound comprising ingredients of such character and combined in such proportions as to produce a compound having maximum efficiency for the purpose.

Various kinds of sweeping compounds are used on floors, wooden, linoleum, tile and varnished concrete.

The qualities desirable in a good sweeping compound are that the compound shall gather and take up the dust and leave no undesirable residue.

My compound effects another desirable result in that it gives to the floor a certain degree of polish not secured with compounds heretofore used.

In the compounds with which I am familiar, there is a considerable content of fine sawdust. This has a disadvantage in that it gets into the cracks in wood floors and some tile floors and is hard to get out.

My compound comprises finely divided or ground cotton fabric, finely divided or ground rubber, preferably with a sulphur content chemically combined or added in a free state, oil, and fine sand, preferably silica sand.

The cotton or finely divided cloth fabric and the rubber may, of course, be secured in different ways, but I preferably use old automobile tires, which are finely ground up. I have discovered that these tires have about the proper cotton fabric and rubber content for making a satisfactory sweeping compound. It would, of course, be possible to secure the finely divided fabric and rubber from other sources, but I prefer to use the old or used tires, commonly called castings, because of the low price at which they can be secured.

The oil used is preferably paraffin oil, preferably the class commercially sold as No. 1, the specifications of which are substantially as follows: gravity (Baumé scale) 24 to 30, fire point, 365 to 375, Fahrenheit, viscosity at 100 degrees Fahrenheit, 70 to 80, cold test 20 to 25 Fahrenheit.

The sand employed is preferably a silica sand of a fineness to pass through a screen of 28 mesh to the inch.

In compounding the ingredients, I preferably use two bushels by bulk of the product of the tires finely ground to one bushel of the sand, four and one-fourth gallons of paraffin oil, and three and three-fourths pounds of coloring matter. The coloring matter is used in order to give to the product a uniform and pleasing color.

In the mixing of the ingredients, the cotton and rubber product and the sand are preferably thoroughly mixed first. The coloring may be put into the oil and the coloring and the oil then thoroughly mixed with the other ingredients.

The finished product is packed in any suitable containers. It has one advantage in that it may be packed, stored and shipped in sacks.

In the practical use of this sweeping compound, the desired amount of the compound is sprinkled over the floor to be swept and the floor may then be swept with brooms in the ordinary way.

The peculiar ingredients of the compound are such that it gives the desired effect of a sweeping compound to a maximum degree.

The finely divided cotton or fabric collects and holds the dust, so that practically no dust is raised by the sweeping operation. The oil, of course, contributes to this desirable function.

The sand is an abrasive and helps in cleaning the floor, and it is also found that it leaves a very fine, almost invisible residue, which is considered desirable.

The rubber serves as a polisher during the sweeping and also deposits a fine residue, which has a polishing effect on the floors used for walking on or the like.

In this connection, I desire to say that I consider the rubber one of the important ingredients in this compound. Buffed rubber is an excellent article to use on dancing floors.

In this connection, it should perhaps be mentioned that the bulk of this compound is much greater compared to its weight than the bulk of ordinary sweeping compounds heretofore used. This is a feature of some importance because it involves the fact that my compound is fluffier than those having large wood content. It is more easily swept

from the floor and it takes up and retains the dust with considerably more effectiveness on account of this quality.

Another important beneficial result arising from the bulkiness of this product may be mentioned. Wood body sweeping compound, if left in any substantial amount collected at one place on the floor, deposits oil on the floor and thus leaves grease spots, whereas my more bulky and fluffy compound will not have this undesirable result.

The fact that no oil is deposited on the floor in any undesirable degree by my compound is probably also partly due to the fact that the cotton absorbs and retains the oil better than a wood content.

The sand has the same effect as in other compounds having the same, and the rubber performs a function not performed in any other sweeping compound, with which I am familiar, both in its polishing effect during the sweeping operation and in the almost invisible residue, which it leaves from the sweeping operation.

I have therefore produced a sweeping compound, which is more effective in accomplishing its purpose, due to the nature and

qualities and proportions of the ingredients employed, and which has the polishing effect not secured with other sweeping compounds.

My compound can also be made at a relative low cost, because of the availability of large quantities of used automobile casings.

The relative proportions of the ingredients of this compound may be varied to some degree without losing the beneficial results and effects of the compound and it is my intention to cover by the claims of my patent, any such modifications in the elements or in the proportions thereof as may be reasonably included within the scope of my invention.

I claim as my invention:

1. A sweeping compound consisting of finely divided old automobile tire casings, sand and paraffin oil.

2. A sweeping compound consisting of finely divided old automobile tire casings, sand and paraffin oil in substantially the proportions by bulk of two bushels, one bushel and four and a quarter gallons respectively.

GENEVIEVE L. SECOY.
